CLAIM

The ornamental design for a display screen or portion thereof with animated graphical user interface, as shown and described.

DESCRIPTION

FIG. 1 is a front view of a first image of a display screen or portion thereof with animated graphical user interface showing the claimed design;

FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a front view of a sixth image thereof; and,

FIG. 7 is a front view of a seventh image thereof.

The outermost broken lines illustrate an electronic device, which is the environment of the design, and forms no part of the claimed design. The remaining broken lines illustrate portions of the display screen and portions of the graphical user interface that form no part of the claimed design.

The appearance of the animated images transitions between the images shown in FIGS. 1-7. The process or period in which one image transitions to another forms no part of the claimed design.

The broken lines shown in the Figures are included to show unclaimed subject matter only and form no part of the claimed design.
